UNITED STATES PATENT OFFICE

169,140

COMBINED SUCTION CLEANER AND CART

Richard E. Hedstrom, Bloomington, and
Basil M. Barrett, Wilmette, Ill.

Application November 24, 1950, Serial No. 13,106

Term of patent 3½ years

(Cl. D9—2)

To all whom it may concern:

Be it known that we, Richard E. Hedstrom and Basil M. Barrett, citizens of the United States of America and residents of Bloomington, State of Illinois, and Wilmette, State of Illinois, respectively, have invented a new, original, and ornamental Design for a combined Suction Cleaner and Cart, of which the following is a specification, reference being had to the accompanying drawing, forming a part hereof and wherein:

Fig. 1 is a side elevational view of a combined suction cleaner and cart, showing our new design;

Fig. 2 is a front elevational view thereof;

Fig. 3 is a top plan view thereof; and

Fig. 4 is a bottom plan view thereof.

We claim:

The ornamental design for a combined suction cleaner and cart, substantially as shown.

RICHARD E. HEDSTROM.
BASIL M. BARRETT.
